[57] CLAIM

The ornamental design for a floor to seat vehicle console, as shown and described.

DESCRIPTION

FIG. 1 is a top perspective view of a floor to seat vehicle console showing my new design in use;

FIG. 2 is a left side elevation view thereof the right side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of a vehicle interior in FIG. 1 is for illustrative purposes only and form no part of the claimed design.
